SAFETY RAZOR

Filed Feb. 3, 1926

INVENTOR
Jacob Schick
BY
Wm. H. Campfield,
ATTORNEY

UNITED STATES PATENT OFFICE

JACOB SCHICK, OF EAST ORANGE, NEW JERSEY, ASSIGNOR TO MAGAZINE REPEATING RAZOR COMPANY, A CORPORATION OF NEW JERSEY

SAFETY RAZOR

Application filed February 3, 1926. Serial No. 85,632.

This invention relates to an improved safety razor of the type that utilizes a stack of blades and feeds them one at a time from the stack, but the razor is designed to require the interposition of a human agency by transferring the blade by hand to the guard. This placing of the blade in shaving position in the guard is possible by reason of the blades being projected, one at a time, when desired 5 so that they can be grasped and withdrawn entirely from the magazine that contains them.

The invention therefor embodies a razor with means for positively feeding a blade at a time from the stack, then withdrawing the blade so fed and placing it in the holder.

The razor is simple to operate, is cheap to manufacture, and keeps the blades secure and in a water-proof compartment.

20 The invention also relates to certain details of construction which will be herein-after more fully described and finally embodied in the clauses of the claims.

The invention is illustrated in the accompanying drawings in which Figure 1 is a face view of a razor embodying my invention with the lower part in section. Figure 2 is a section of the lower part of the handle with the magazine partly withdrawn to place a blade 25 in position to be ejected and Figure 3 is a similar view with the magazine returned and the single blade left exposed. Figure 4 is a section on line 4-4 in Figure 1. Figure 5 is a perspective view of the magazine and a holder that may be employed therewith. Figure 6 is a section of the guard showing a form for quickly and positively receiving and securing a blade.

The razor comprises a handle and a guard, 40 the guard being preferably mounted on a post. In the drawing I show a handle 10, a post 11 and a guard 12. The handle has a recess or chamber 13 which is adapted to receive a stack of blades 14. For convenience 45 in handling, the blades are stacked in a magazine 15 which is slidable in the handle. The magazine is best handled when in a holder, one form of holder being shown at 16, which holder consists of a strip of metal which engages the end walls of the magazine by means

of the fingers 17 and 18. The lip 19 at the end of the holder is a handy means for operating the holder and sliding it back and forth when it is reciprocated to feed a blade from the stack. The stack of blades is pressed 55 toward the top of the magazine by a spring and I show the spring 20 struck up from the holder 16 and projecting into the bottom of the magazine which is open except for the flanges 21 to support the blades before they 60 are inserted into the razor. The magazine is provided with ears 22 to hold the stack of blades at the top, these ears extending only a slight distance across the top of the top blade.

On the wall of the recess opposite the top of the stack I provide means for engaging the top blade and in the drawing I illustrate a shoulder or projection 23 which is centrally located to allow the ears 22 to pass it.

It will be evident that when the magazine is withdrawn to the position shown in Figure 2 it allows the top blade to be pushed so that it engages the wall 24 below the shoulder 23. When the magazine is pushed in 75 again the blade at the top is fed from the stack as shown at 24a in Figure 3 and is thus projected from the razor so that it can be grasped by the fingers and withdrawn entirely from the razor.

This construction is an example of the razor and it will be evident that other means may be employed for placing the blades successively in exposed position from which position they can be readily withdrawn.

The blade is carried by hand after it is withdrawn from the handle and is then placed in the guard. The guard can be constructed to receive the blade edgewise or laterally but I illustrate one form of guard in which the 80 guard 12 has its fender or guard piece 25 pivoted as at 26 and with a finger-piece 27. The finger-piece is pressed in when a blade is to be inserted and the blade, shown at 28 in Figure 6, is deposited between the fender 25 and the 85 lip 29. Studs 30 limit the rearward movement of the blade. The spring 31 holds the fender in position and is stiff enough to resist the pressure on the fender in shaving. A stiff metal spring or a block of resilient mate- 100

rial such as rubber is usually used, this requiring a positive, strong pressure to open the guard to receive a razor blade and when released, holding the blade firmly in place.

5 The recess 13 is closed by the cap 32 which is either slid or screwed on to the end of the handle, the cap having a marginal flange 33. The cap when removed to permit reciprocation of the stack of blades in the magazine can be used as a tool for withdrawing the holder 16. This will be evident from Figure 1 in which view I show the cap in dotted outline illustrating that it can be hooked over the lip 19 and thus used for pulling the holder from 10 the handle the required distance, thus making this withdrawal easier than if done by the finger nail.

15 I claim:

1. A razor comprising a handle, a magazine containing a stack of blades, a holder for 20 the magazine and which with the magazine is slidable in the handle, a projection to engage and feed a blade from the stack when the holder and the magazine are reciprocated, the 25 blade so projected being placed so as to be grasped by the hand, a cap adapted to fit over and close the handle, the cap having a marginal flange, a lip on the holder disposed so that when the holder is in place in the handle 30 the flange of the cap, when removed from the handle, can be used as a tool for engaging and withdrawing the holder.

2. A razor comprising a casing, a holder 35 slidable in the casing and adapted to be partially withdrawn therefrom, the holder including a lip at its outer end, and a flanged cap for closing the end of the casing and adapted for engagement with the lip for withdrawing the holder.

40 In testimony whereof I affix my signature.
JACOB SCHICK.
